UNITED STATES PATENT OFFICE.

GEORGE W. RANK AND PHILIP M. HOFFMANN, OF INDIANAPOLIS, INDIANA.

SAFETY DEVICE FOR POWER SQUARING-SHEARS AND SIMILAR MACHINES.

1,190,670.

Specification of Letters Patent. Patented July 11, 1916.

Application filed November 14, 1914. Serial No. 872,123.

To all whom it may concern:

Be it known that we, GEORGE W. RANK and PHILIP M. HOFFMANN, citizens of the United States, residing at Indianapolis, Marion county, and State of Indiana, have invented and discovered certain new and useful Improvements in Safety Devices for Power Squaring-Shears and Similar Machines, of which the following is a specification.

Our invention relates to safety devices for power squaring shears and similar machines and its object is to provide means whereby the operator of the machine will be protected against injury by the shearing blade.

To this end our invention is embodied in preferable form in the attachment herein-after described and illustrated in the accompanying drawings.

In these drawings, Figure 1 is a front view in elevation of a power squaring shears with our invention applied thereto; Fig. 2, a sectional end view on the line 2—2 of Fig. 1; Fig. 3, a horizontal section on the line 3—3 of Figs. 1 and 2; Fig. 4, a section on the line 4—4 of Fig. 1; Fig. 5, a detail section on the line 5—5 of Fig. 3; Fig. 6, a detail section on the line 6—6 of Fig. 5, and Fig. 7, a section on the line 7—7 of Fig. 3.

Referring to the drawings, 1 is the frame of a power squaring shears, 2 a vertically reciprocating shear blade and 3 the bed on which the work, such as a sheet of metal, is adapted to be placed. In machines of this class a sheet of metal is adapted to be placed upon the work bed and moved forward by the hands of the operator until it is positioned on the bed under the blade at the line where it is desired to cut the sheet. The operator then throws the driving means into engagement with the actuating mechanism of the blade by operating a clutch through a foot pedal, and therewith the blade is forced down through the sheet of metal, and then the sheet is withdrawn by hand and another one substituted. In the operation of such machines it is necessary for the operator to advance his hands close to the cutting blade in both placing and withdrawing the work. This is a dangerous operation and frequently results in serious injury to the operator. It also frequently happens, in the operation of the machine, that as the blade is being raised the clutch between the blade operating mechanism and the driving

means is thrown into engagement, thus causing the blade to repeat its operation while the operator is still attempting to withdraw the work from underneath the same. This action also is the cause of numerous accidents.

Our invention aims to guard against the occurrence of accidents of the above kind by providing means for holding the clutch mechanism positively out of engagement until the same is again operated by the direct application of the foot of the operator to the pedal lever, and also to provide means for preventing the entrance of the fingers of the operator between the shearing blade and the work during the cutting operation.

The shearing blade is adapted to be reciprocated vertically by rods 4, which are operated by eccentrics 5 on a shaft 6, extending across the machine. The shaft 6 is provided at one end with a large gear wheel 7, known as a bull wheel, which is driven by a gear 8, mounted on the end of a driving shaft 9. This bull wheel is mounted loosely on the shaft 6 and is adapted to be positively connected thereto by means of a suitable clutch mechanism. The clutch mechanism shown in the drawings is of the form usually employed in power squaring shears and comprises a spring pressed pin 85 mounted in a socket 11 in a collar 12 which is fixed upon the shaft 6, and the end of which pin is constantly forced outward by a spiral spring 13 mounted within the socket. The outer end of the pin is adapted to engage either one of two recesses 14 formed in the bull wheel. When the pin is forced outwardly by its spring into one of the recesses, the bull wheel will be fixedly connected to the collar and hence the shaft 90 6 will be driven through the driving connection between the gears 8 and 7.

The pin 13 is held normally out of engagement with the bull wheel by the end of the arm 15 of a bell crank lever detent, the outer end of which is beveled and is adapted to project into a circumferential slot 16 cut in the hub of the bull wheel. When the arm is depressed, it holds the pin out of engagement with the wheel and when raised, it permits said pin to establish automatically a driving connection between the bull wheel and shaft. This controlling detent is connected to and operated by the foot treadle, as is usual, and to this end

the bell crank is provided with a rearwardly extending arm 17, which has a pin 18 at its outer end which is adapted to engage an elongated slot 19, formed in the upper end of a link 20, which is pivoted at its lower end to an arm 21. This arm is pivoted at the other end to a rocking shaft 22 which is adapted to be operated by a treadle 23. A spring 24 connects the arms 21 and 17 and when the arm 21 is forced downwardly by the application of pressure to the treadle, a tension will be imposed on said spring which will act to pull the arm 17 downwardly with a quick movement, thus releasing the arm 15 from engagement with pin 18. The slot 19 permits the link 20 to move downwardly a considerable distance relatively to the arm 17 so that the latter arm will not be actuated by the downward movement of the link. During the downward movement of the arm 21 the tension will continue to be imposed upon the spring 24 but such tension will not be sufficient to cause a movement of the arm 17 until the locking latch bar hereinafter described has been withdrawn from locking engagement with the detent arm 15.

The detent and clutch pin above described are substantially the same as are employed in all power squaring shears for controlling the connection of the blade operating mechanism with the driving mechanism.

The clutch locking feature of our safety device, the object of which is to prevent the repeat operation above referred to, will now be described. Mounted on a plate 25 secured to and extending from the main frame 1, is a horizontally sliding locking latch bar 26 which is provided with a notch 27 at its outer end, leaving a projecting latch toe 28 which is adapted to extend over the upper face of the arm 15. This latch bar when projected serves to lock the arm down in position to prevent the engagement of the pin with the bull wheel and said wheel is thus prevented from operating the shaft 6 except when the latch bar is positively withdrawn by the operation of the power lever as hereinafter described, and thus an accidental protraction of the pin, causing an unintended repeat operation of the blade is prevented. Engaging a pin 29 on the latch bar is a slot formed in the upper end of an arm 30 of a bell crank lever, the lower arm 31 of which is pivoted on a pin 32 fixed to the lower end of a rod 33. A lower rod 33 has an upper hooked end which projects into a slot 35 formed in the rod 36 and takes over the pin 32. The lower end of rod 33 is pivoted at 34 to the link 20 near the lower end of the latter and is adapted to be operated in a downward movement by said link. The upper end of the rod 36 is pivoted to a

crank 37 fixed to a shaft 38. Fixed on the shaft 38 is an arm 39 pivoted to a link 40, the lower end of which is pivoted to a lug projecting outwardly from the face of a guard member 41 which is mounted in suitable guide bearings in the frame 1 of the machine in front of the shearing blade. This guard member preferably consists of horizontal strips connected by open wire work or similar reticulated material 42 which is provided for the purpose of enabling the operator to observe the movement of the shearing blade behind the guard member. This guard member is adapted to be moved vertically downward in front of the shearing blade immediately before the latter starts in its downward operative stroke and it is carried in such movement to a position sufficiently close to the work which is to be cut, to prevent the entrance of the fingers of the operator, as he pushes the work forward, under the shearing blade. A stop 44 limits the downward movement of the guard member. The rod 36 is divided and is provided with an adjusting device consisting of a turn buckle 45, whereby the operating mechanism of the guard member may be adjusted to suit the conditions of the clutch operating mechanism and of the connections between the parts. A return spring 36' is connected to the rod 36 and serves to draw said rod and the guard member upwardly. A plate 42' is movable downwardly with the blade and 43 are cushioning springs for said plate mounted on guide pins 44. This construction is usually in shear machines and forms no part of our invention. A friction brake 45' engages the collar 12 and prevents rotation thereof by momentum after the clutch pin is withdrawn.

The operation of the device is as follows: The shaft 9, gear 8 and bull wheel 7 are continuously driven. In order to cut a sheet of metal, the operator places the same upon the bed 3 of the machine under the shearing blade and then depresses the foot treadle 23 for the purpose of positively connecting the bull wheel with the blade operating shaft 6. In this depression of the foot treadle, the arm 21 and link 20 will be carried downwardly, the movement of the former imposing a tension on the spring 24, and at the same time will pull downwardly the rod 33 which is connected to the bell crank arm 31, and also carry down rod 36 and during this movement the slot 19 will move downwardly with respect to the pin 18 thus permitting the operation of the bell crank having the arm 31 and also of the rod 36 before the upper end of slot 19 contacts with the arm 17, of the detent bell crank. As the rod 33 is pulled downwardly, moving the connected rod 36, shaft 38 will be rocked, operating the arm 39 and link 40 so as to force the guard

member 41 to travel downwardly in front of the blade. This member will move down until it strikes the stop 44'. The guard is set to move down to the upper line of the work of the maximum thickness that the machine is adapted to accommodate. This condition not only prevents the entrance of the fingers of the operator between the bed and blade but also serves to prevent the operation of the machine when a plate of excess thickness is attempted to be inserted between the blade and bed. At the same time the arm 30 of the first bell crank member will carry the latch bar 26 to the left, releasing the under face of the bar from engagement with the arm 15 of the clutch detent bell crank, whereby the detent will slip into the recess formed by the reduced toe 28, so that said detent will be in unlocked position and ready to be operated to release the clutch pin 13. Owing to the relative lengths of travel of the latch bar and guard member, the former will not be released from the detent until the guard member has moved down to its limit of travel. As soon as the latch bar has released the detent 15, a sufficient tension will have been imposed on the spring 24 to rock the arm 17, and snap the arm 15 out of the path of the pin 13 and permitting said clutch pin to engage with the bull wheel whereupon the latter is locked to the shaft 6 and said shaft will be operated so as to rotate the eccentrics 5 and carry downward the shearing blade 2 to perform the cutting operation. The spring 24 serves to give a quick movement to the arm 15 before the end of the slot 19 reaches the pin 18. After the cutting operation has been performed and the blade again raised to its uppermost position, the foot treadle is released whereupon springs 46 will carry said treadle and the connected parts 21 and 20 and the bell crank 17-15 back to normal position and as soon as the arm 15 has been moved into alignment with the clutch pin 13, said clutch pin in its revolution will ride against the inclined part of the end of the arm 15 and be retracted so as to release the bull wheel. The rod 36 will be carried upwardly by the return spring 36' and as the lower end of the slot 35 in said rod contacts with the pin 32, the bell crank 31-30 will be rocked so as to throw the latch bar 26 to the right and above the detent lever 15 which has been previously thrown down into detaining position, thus locking the clutch pin safely in retracted position and preventing the arm 15 from being accidentally raised by the jarring of the machine and consequently preventing the accidental engagement of the pin 13 with the bull wheel, thus avoiding the liability of an improper repeat operation of the shearing blade. The guard member 41 will be carried upward by spring 36'. If desired, the

clutch locking mechanism may be employed without the use of the guard member 41, but, of course, the latter is a highly important feature in the prevention of injury to the operator.

Having thus described our invention, what we claim is:—

1. In combination with a machine including a member to be driven for operation upon work supplied to the machine, operating mechanism for said member, driving means for said operating mechanism, a clutch between said driving means and operating mechanism, a detent for holding said clutch out of engagement, a locking member for said detent automatically movable into position to lock said detent in clutch detaining position, a single common foot operated member for operating both said detent and said locking member in the same movement of the operating member and means of connection between said operating member and said detent and locking member permitting the operation of the latter before the operation of the detent and means for automatically and successively restoring the detent and locking member to locking positions.

2. In combination with a machine including a member to be driven for operation upon work supplied to the machine, operating mechanism for said member, driving means for said operating mechanism, a clutch between said driving means and said operating mechanism, said clutch including a spring pressed automatically engaging clutch pin, a pivoted detent for holding said clutch pin normally out of clutching engagement, a sliding latch bar adapted to bear against said detent for locking it in detaining position, an operating foot treadle under the control of the operator of the machine, operative connections between said operating treadle and the locking member and detent respectively, said locking member connection permitting the withdrawal of the latch bar from the detent preliminarily to the withdrawal of the detent from the clutch pin and means for successively and automatically restoring the detent and latch bar to locking positions.

3. In combination with a machine including a member to be driven for operation upon work supplied to the machine, operating mechanism for said member, driving means for said operating mechanism, a spring pressed automatically engaging clutch pin between said driving means and operating mechanism, a pivoted detent for holding said clutch out of engagement, a sliding latch bar for locking said detent in detaining position, a connection between said treadle and said locking latch bar for retracting the latter, and a spring and a lost motion connection between said treadle.

and said detent whereby said detent will be operated only after the latch bar has been withdrawn and after tension has been imposed upon said spring by the movement of the treadle.

4. In combination with a machine including a part to be driven for operation upon work supplied to the machine, mechanism for operating said part, driving means, a clutch intermediate said driving means and operating mechanism, a detent for holding said clutch out of operative position, a locking latch bar adapted to engage said detent, a treadle for operating said detent and latch bar, an operating link, means of connection between said link and latch bar and a lost motion and flexible connection between said link and said detent whereby the locking member will be released preliminarily to the release of the detent, and means for automatically and successively restoring the detent and locking member to locking positions upon the release of the treadle, substantially as described.

25 5. In combination with a shear machine including a movable blade, a work bed, a guard member mounted in front of the blade and movable toward and away from the work bed, operating mechanism for the blade, driving means, a clutch between said mechanism and means, a detent for holding said clutch out of operation, a locking member for holding said detent in clutch detaining position, a treadle, and means of operative connection between said treadle and the guard member, detent and locking member respectively, substantially as described.

6. In combination with a machine including a member to be driven for operation upon work supplied to the machine, a work bed, a guard member mounted in front of the driven member and movable toward and from said work bed, driving means for said driven work member, a controlling member for throwing said driving means into operative connection with the driven member, means of operative connection between said controlling member and the guard member operable to hold the guard member constantly down in guarding position during the successive movements of the driven

member in a continuous operation of the machine.

7. In combination with a machine including a member to be driven for operation on work supplied to the machine, driving means for said member, a controlling member for establishing a connection between said driving means and said driven member, a work bed, a guard member mounted adjacent to the driven member and movable toward and from the bed, means of operative connection between the controlling member and said guard member for moving the guard member into guarding position when the controlling member is actuated, said connecting means holding the guard member down in operative position during successive movements of the driven member, when the machine is continuously operated and means for limiting the downward movement of the guard toward the bed to a line spaced above the work to thereby permit the repeated insertion of work under the guard member while the same is in guarding position.

8. In combination with a machine including a member to be driven for operation upon work supplied to the machine, driving means for said driven member, a treadle, a clutch between the treadle and driving means, a detent for holding said clutch out of operation and having means of connection with the treadle whereby the detent is held out of detaining position with respect to the clutch while the treadle is depressed and a guard member mounted adjacent to the driven member and means of connection between the treadle and said guard member adapted to hold the guard member down in guarding position while the treadle is depressed.

In witness whereof, we have hereunto set our hands and seals at Indianapolis, Indiana, this 11th day of November A. D., 1919, nineteen hundred and fourteen.
